UNITED STATES PATENT OFFICE.

GEORGE FISCHRUPP, OF CHICAGO, ILLINOIS.

FOLDING BED.

1,078,910.

Specification of Letters Patent.

Patented Nov. 18, 1913.

Application filed December 13, 1909, Serial No. 532,791. Renewed May 7, 1913, Serial No. 766,207.

To all whom it may concern:

Be it known that I, GEORGE FISCHRUPP, a citizen of the United States of America, and a resident of Chicago, in the county of Cook 5 and State of Illinois, have invented certain new and useful Improvements in Folding Beds, of which the following is a specification.

This invention relates to that type of folding beds in which the bed forming sections are connected together in a longitudinal manner and are adapted to fold together into a box or housing to provide a seating fixture for day use. And the present improvement has for its object to provide a simple and efficient construction and combination of the bed forming sections, which in an opening movement of the sections to provide a bed surface, the parts automatically 10 rise and are shifted laterally into an elevated plane to the front of the supporting box or housing, to afford an extended and roomy bed surface, and which in a closing movement of the sections to provide a seating surface, the parts automatically descend and move back laterally into the supporting box or housing, all as will hereinafter more fully appear.

In the accompanying drawings: Figure 1, 15 is a transverse sectional elevation, illustrating the present invention applied to a box couch bed, and with the parts in a closed condition. Figs. 2, 3 and 4, are similar views showing the parts in a partly open and fully open condition, and graphically illustrating the movement of the parts and their coacting relation. Fig. 5, is a detail plan view of the parts in an open condition.

Similar numerals of reference indicate 20 like parts in the several views.

Referring to the drawings, 1 represents the box or housing to which the bed sections hereinafter described are attached, to be supported and housed thereby. In the construction shown in the drawings such housing is of the ordinary oblong box form known to the trade as the box couch bed; any other ordinary and suitable form of housing may however be used, as the present improvement is capable of application 25 to the sofa and like type of folding beds now in general use.

2 is a longitudinal rail provided at its respective ends with short upright members or links 3, and attached by means of pivot pins 4 passing through the lower parts of

the members 3 and into the end walls of the housing 1 as shown, to provide a pivotal attachment of said members to the housing for purposes hereinafter stated.

5 are intermediate links of the T form shown, and pivoted by their intermediate lateral arms 6 to the upper ends of the aforesaid upright members 3 of the rail 2 by suitable pivot bolts or rivets as shown.

7 and 8 are counterpart upper and lower skeleton frame sections of the rectangular form shown, and which are pivotally connected to the opposite ends of the aforesaid intermediate links 5 by hinge connections 70 which permit of an independent quarter turn between the parts in their movements of folding and unfolding hereinafter described.

The intermediate links 5 and frame sections 7 and 8, above described, constitute a marginal supporting frame to which is attached the usual elastic wire webbing (not shown) usually employed in bed frame to support an ordinary mattress. Said marginal frame in its folded condition as shown in Fig. 1, forms a space for holding the mattress, etc., as usual in folding beds.

9 are lifting levers pivoted to the end bars of the lower frame section 8 aforesaid, with 85 their lower ends having bearing upon bottom rails 1' of the housing 1, while their upper ends are pivotally connected to pull bars 10, now to be described.

10 are pull bars pivotally connected at 90 one end to the lifting levers 9, above described, and at their opposite ends to the aforesaid intermediate links 5 at points adjacent to the points of pivotal attachment of the lower frame section 8 to said links 5. 95

11 are long radius links pivoted at one end to the end walls of the housing 1, and at the other end to the intermediate links 5, preferably at the same point of pivotal connection as the pull rod 10 to said intermediate links 5.

The operation of the parts is as follows: With the parts in the closed or seat condition illustrated in Fig. 1, the operator first tilts back the cover portion of the box or housing 1, after which an upward pull is made upon the free end of the upper frame section 7 to move the same into the upright position shown in Fig. 2; such movement taking place without any movement of the other parts of the bed frame. The operator exerts an outward and downward pull

on said free end of the upper frame section 7, and by such movement gradually tilts the intermediate links 5 from their previous upright position into the horizontal position indicated in Fig. 4. During such operation the intermediate links 5, through the instrumentality of the pull bars 10, levers 9 and bottom rails 1', raises the rear side of the lower frame section 8 to a plane level with that of the upper frame section 7 and intermediate links 5 aforesaid. Simultaneously with the above described rising movement of the lower frame section 8, the radius links 11, during the tilting movement of the intermediate links 5, acts to push the entire bed frame outward into a convenient position for use as a bed surface. Such outward movement is a pivotal one and takes place upon the pivot bolts 4 of the short upright members 3, before described. In a folding movement of the parts back to the original position shown in Fig. 1, the reverse of the movements above described takes place.

25 The different relative positions of the parts, are serially illustrated in Figs. 1, 2, 3, and 4, of the drawings.

Having thus fully described my said invention what I claim as new and desire to 30 secure by Letters Patent, is:

1. In a folding bed, the combination of a main housing, pivot members attached to said housing, intermediate links pivotally connected to said pivot members, counterpart part marginal frame members pivoted to the respective ends of said intermediate links, and means intermediate of said links and the housing for imparting an upward movement to the frame members and intermediate links in an opening movement of the parts, the same comprising pull bars, levers and horizontal guiding means on the main housing, substantially as set forth.

2. In a folding bed, the combination of a main housing, pivot members attached to said housing, intermediate links formed with lateral arms for pivotal connection with said pivot members, counterpart marginal frame members pivoted to the respective ends of said intermediate links, and means intermediate of said links and the housing for imparting an upward movement to the frame members and intermediate links in an opening movement of the parts, the same comprising pull bars, levers and horizontal guiding means on the main housing, substantially as set forth.

3. In a folding bed, the combination of a main housing, a rail disposed longitudinally between the end walls of said housing and provided with upright end members, intermediate links formed with lateral arms for pivotal connection with said end members, counterpart marginal frame members pivoted to the respective ends of said inter-

mediate links, and means intermediate of said links and the housing for imparting an upward movement to the frame members and intermediate links in an opening movement of the parts, the same comprising pull bars, levers and horizontal guiding means on the main housing, substantially as set forth.

4. In a folding bed, the combination of a main housing, short upright members pivoted at their lower ends to said housing, intermediate links pivoted to said upright members, counterpart marginal frame members pivoted to the respective ends of said intermediate links, and means intermediate of said links and the housing for imparting an upward movement to the frame members and intermediate links in an opening movement of the parts, the same comprising pull bars, levers and horizontal guiding means on the main housing, substantially as set forth.

5. In a folding bed, the combination of a main housing, short upright members pivoted at their lower ends to said housing, intermediate links formed with lateral arms for pivotal connection with said upright members, counterpart marginal frame members pivoted to the respective ends of said intermediate links, and means intermediate of said links and the housing for imparting an upward movement to the frame members and intermediate links in an opening movement of the parts, the same comprising pull bars, levers and horizontal guiding means on the main housing, substantially as set forth.

6. In a folding bed, the combination of a main housing, short upright members pivoted at their lower ends to said housing, intermediate links pivoted to said upright members, counterpart marginal frame members pivoted to the respective ends of said intermediate links, radius links pivotally attached to the aforesaid intermediate links and to the housing, and means intermediate of said intermediate links and the housing for imparting an upward movement to the frame members and intermediate links in an opening movement of the parts, the same comprising pull bars, levers and horizontal guiding means on the main housing, substantially as set forth.

7. In a folding bed, the combination of a main housing, short upright members pivoted at their lower ends to said housing, intermediate links formed with lateral arms for pivotal connection with said upright members, counterpart marginal frame members pivoted to the respective ends of said intermediate links, radius links pivotally attached to the aforesaid intermediate links and to the housing, and means intermediate of said intermediate links and the housing for imparting an upward movement to the frame members and intermediate links in

an opening movement of the parts, the same comprising pull bars, levers and horizontal guiding means on the main housing, substantially as set forth.

5 8. In a folding bed, the combination of a main housing, a rail disposed longitudinally between the end walls of said housing and provided with upright end members, intermediate links formed with lateral arms for 10 pivotal connection with said end members, counterpart marginal frame members pivoted to the respective ends of said intermediate links, radius links pivotally attached to the intermediate links and to the

housing, and means intermediate of said intermediate links and the housing for imparting an upward movement to the frame members and intermediate links in an opening movement of the parts, the same comprising pull bars, levers and horizontal 15 guiding means on the housing, substantially 20 as set forth.

Signed at Chicago, Illinois, this 10th day of December 1909.

GEORGE FISCHRUPP.
